UNITED STATES PATENT OFFICE.

RAYMOND I. HILL, OF ELYRIA, OHIO, ASSIGNOR, BY MESNE ASSIGNMENTS, TO W. R. HUNTINGTON.

RESILIENT HEEL LIFT.

Application filed November 26, 1917. Serial No. 203,983.

To all whom it may concern:

Be it known that I, RAYMOND I. HILL, a citizen of the United States, residing at Elyria, in the county of Lorain and State of Ohio, have invented certain new and useful Improvements in Resilient Heel Lifts; and I do hereby declare the following to be a full, clear, and exact description of the invention, such as will enable others skilled in the art to which it appertains to make and use the same.

One of the objects of my invention is to provide an improved resilient heel lift in which the heel lift automatically maintains closed the seam between the rubber and leather while the same is in working position, thereby preventing the ingress of dirt and water.

I also aim to provide a device which is so constructed as to take up any slack which will result from the loosening of the nails or washers, and which will not project beyond the edge of the leather section of the heel or shoe when the parts are worn.

Another object of my invention is to provide a device with a relatively large trimming space inside the heel edges and one in which fewer nails or fastening means and no cement are required to attach the device to a shoe.

These and other objects of my invention will be understood from a description of an embodiment of the invention.

Fig. 1 is a plan view of an embodiment of my invention showing the tread or wear face of a heel lift. Fig. 2 is a front elevation of the embodiment shown in Fig. 1. Fig. 3 is a rear end elevation thereof. Fig. 4 is a side elevation thereof. Fig. 5 is a cross section taken along the line 5-5 in Fig. 1. Fig. 6 is a section taken along the lines 6-6 in Fig. 1. Fig. 7 is a section thru a shoe heel upon which there has been mounted a device like that illustrated in Figs. 1 to 6, inclusive. Fig. 8 is a plan view of the lift as shown in Fig. 7. Fig. 9 is a plan view of the embodiment shown in Fig. 1 showing the attaching face of the heel. Fig. 10 is a section thru a second embodiment of my invention. Fig. 11 is a section thru a third embodiment. Fig. 12 is a section thru a fourth embodiment.

Referring now to the drawings, and first to the embodiment of the invention shown in Figs. 1 to 9 thereof, at 10 is illustrated a

heel section, in the embodiment shown a lift, made of some resilient material, preferably of rubber or rubber composition. The general outline of the lift is concavo-convex, being concave on the attaching face 11 and convex on the tread face 12.

For convenience in the description, I will speak of the heel as being in normal position when the parts are in the position illustrated in Figs. 1 to 6 inclusive and 9, and in working position when nailed on the heel, as shown in Figs. 7 and 8. In the embodiment shown, when the lift, in normal position, is laid upon a smooth surface, the side edges 13, 13' and the rear edge 14 engage the smooth surface, while the front or breast edge constitutes a slight arch between the breast corners 16 and 16', as indicated at 40.

A protuberance 17 extends outwardly from the central portion of the attaching face, preferably to a point where it engages or about engages a smooth surface upon which the lift may be laid with its attaching face next to such surface when the lift is in normal position. In the embodiment shown, the protuberance 17 is at the center of the attaching face and is elliptical in outline, as illustrated in Fig. 1.

With this arrangement it will be seen that there is an arch 20 in the attaching face, which extends about the central portion thereof and which has substantially the outline of the lift. Such arch extends from the edges 13, 13' and 14 and 15 to the summit 18 of the protuberance 17. The convex portion of the lift is provided with a depression or crater 21, which corresponds, or substantially corresponds, to the outline of the protuberance 17, so as to maintain a uniform or substantially uniform thickness throughout the body of the lift, so that when the lift is flattened into working position, as shown in Figs. 7 and 8, there will be irregularity in neither the attaching nor tread surfaces of the heel.

I find it best to provide a slot, such as is shown at 22, along the crest of the protuberance, in order to prevent crowding of the material when the heel lift is in working position. In the embodiment shown, two slots are provided; substantially at right angles to each other. I have illustrated the second slot at 23. It will be obvious that any suitable number of slots bearing any suitable relation to each other may be employed.

Openings 80 for attaching means, such as nails or screws, are placed about the central portion of the lift, preferably about midway between the ends and at or near the apex of the arch 20. Washers 81 should be embedded in the heel, one about each of these openings. By this arrangement I am enabled to place these nail openings so far from the margin of the lift that the same may be readily trimmed to fit various sizes of shoes.

When it is desired to attach the heel to a shoe, it is flattened out upon the shoe heel and trimmed to suitable size. The arches 15 are flattened out, the slots 22 and 23 are closed and the nails or screws driven into the shoe at the central portions of the arches, as will readily be seen.

When in working position, there is always a tendency, due to the resilience of the material of which the lift is composed, for the lift to resume its normal position; consequently, the central portion and the marginal edges of the heel will always be forced against the leather surface, preventing any projection of the lift from the edges of the heel, always causing the rubber lift, and particularly the edges and center thereof, to cling to the edges of the shoe heel, thereby preventing the ingress of any dirt. It will also be seen that should the nails or washers become loosened in the rubber material of the lift, the slack will immediately be taken up by the lift endeavoring to return to its normal position. Owing to this tendency of the lift to return to normal, thereby sealing the edge of the seam, I find it necessary to employ no more than enough nails to maintain the heel flattened, and thereby avoid the use of a large number of fastening means, employed in many forms of heels in an effort to nail down the margin of the heel lift to the leather.

In the embodiment shown in Fig. 10, the projection is shown at 17, the marginal edges 13, and 13, and the arches at 20, and 20. The crater is shown at 21.

In the embodiment shown in Fig. 11 the projection is shown at 17, the crater at 21, and marginal edges at 13, and 13, and the arches at 20.

In the embodiment shown in Fig. 12, the projections is shown at 17, the crater at 21, the marginal edges at 13, and the arches at 20.

In the embodiments shown in Figs. 10 and 12, the protuberances 17, and 17, are exaggerated, so that when the lifts are flattened out, these excess portions or lugs will be compressed and in tending to resume their normal shape, will always, acting about the fastening means as pivots, cause the edge portions of the lift to hug still tighter the leather part of the heel.

I have shown a heel with a smooth tread

and attaching surface, though it will be understood that I may equip such surfaces with non-slip or cushioning devices or other expedients now old and well known in the art. It will likewise be apparent that I may change the dimensions or shape of the arch, protuberance or crater, without departing from the spirit of my invention, so long as I realize results herein mentioned.

I have shown these embodiments of my invention and the details thereof for the purpose of better describing the invention. I do not wish to be limited to such embodiments or details, as it will be apparent that numerous and extensive departures may be made therefrom without departing from the spirit of the invention.

I claim:

1. In a resilient heel or heel lift, the combination with a body portion having a concave attaching surface with its margin all about its side and rear edges higher than the other parts of the attaching face when the lift is in normal or idle position, so that when placed upside down on a smooth surface such edge engages such surface all about the rear and sides of such face, a protuberance projecting from the central portion of the attaching surface and extending when the heel is in normal position to about a plane passing thru the marginal side or rear edges of the attaching surface, said body portion being provided, when the heel is in normal position, with a convex tread surface and a crater in its central portion of about the contour of the protuberance, said body portion being provided with nail receiving openings about the crater and about midway between the edges of said crater and the edge of the heel and washers about said openings.

2. As an article of manufacture, a resilient heel lift provided on its attaching face, when said lift is in normal position, with an elevated central portion and with an arch around the central portions and adapted to be flattened when the lift is in working position.

3. As an article of manufacture, a resilient heel lift having a double arch in the attaching face of said lift in every plane passing thru and including the central short axis of the lift, said arches adapted to be flattened out when the lift is in working position.

4. In a resilient heel or heel lift, the combination of a body portion having a tread face convex with a concavity in the central portion thereof, both of said surfaces adapted to be flattened out when the device is in working position, said lift having a concave attaching face when in normal position and a protuberance extending from the central part of the attaching face when the lift is in normal position, said concave face be-

ing flattened out when the lift is in working position, means to attach the lift to a shoe heel applied to the body portion of the lift between the margin of the lift and the 5 protuberance, whereby when the lift is attached to the shoe the tread and attaching surfaces are maintained substantially flat, said lift being made of resilient material which always tends to restore the lift to normal position, thereby causing the edges and 10 the central portion of the lift to cling to the surface to which the lift is attached.

5. In a concavo-convex resilient heel or heel lift, the combination of a slit protuberance projecting from the attaching face 15 of said lift and said lift being provided with a depression in its tread surface corresponding to said protuberance.

6. As an article of manufacture, a resilient heel lift provided on its attaching face, when said lift is in normal position, with 20 an arch extending around the central part of the lift, adapted to be flattened when the lift is in working position, and a protuberance extending from the central part 25 of the attaching face of the lift and adapted to be compressed when the lift is attached to a shoe heel.

7. A resilient heel lift having on its attaching face a substantially central elevated portion, and between the latter and the margin a concavity extending all around the elevated portion, and means receiving attaching devices so located that when the lift is applied to a shoe the elevated portion and 30 concavity are flattened out.

8. A resilient heel lift having on its attaching face a substantially central protuberance, a dished or concave surface extending from the margin of the heel inwardly 40 to the base of the protuberance, and means receiving attaching devices so located that when the lift is applied to a shoe the elevated portion and concavity are flattened out. 45

9. A rubber heel having on its attaching face a depression following the entire periphery of the heel and having opposite thereto in the tread surface a ridge surrounding a central depression, the heel having nail holes in the median line of the depression and ridge. 50

In witness whereof I have hereunto signed my name this 19th day of November, 1917.

RAYMOND I. HILL.
